MULTIPLE OILER

Ernest W. Davis, River Forest, Ill.

Application August 2, 1946, Serial No. 687,865

19 Claims. (Cl. 184—7)

1

This invention relates to automatic oiling devices and is particularly concerned with a multiple oiler adapted to supply oil to a plurality of parts, bearings or other surfaces continuously or intermittently at a predetermined rate.

One object of the invention is to provide a low cost dependable oiler provided with sight feed means and with means for individually regulating the rate of flow to each bearing served by the oiler.

Another object of the invention is to overcome a common defect in devices of this character due to the foaming of the oil and the consequent interference with regular feed through the supply tubes.

It is also an object of the invention to provide a simplified electrical pumping device for transferring the oil from a source of supply to the several feed tubes of the system.

A further object of the invention is to provide simple means for conveniently grouping the feed tubes leading from the central supply reservoir in a manner to enhance the appearance of the equipment.

Other objects and advantages of the invention will appear from the following description taken in connection with the drawings, in which:

Fig. 1 is a front elevation of a multiple oiler embodying this invention;

Fig. 2 is a vertical sectional view taken substantially as indicated at line 2—2 on Fig. 1;

Fig. 3 is a detail section taken as indicated at line 3—3 on Fig. 2;

Fig. 4 is a fragmentary perspective view showing an identifying marker for a bearing served by the oiler.

The structure shown in the drawings to illustrate the invention includes a main tank or reservoir 10 which contains a supply of oil and which, as shown in Fig. 2, has mounted within it an electrical pumping unit indicated generally at 12 and disposed in the lower portion of the tank 10. This pump includes a cylinder 14 with a piston 16 mounted for reciprocation therein and urged yieldingly toward the lower limit of its stroke by a spring 18. The lower end of the cylinder 14 is open as indicated at 20, and the cylinder is supported by a base 22 which rests on the bottom of the tank, but is provided with inlet openings 24 through which the oil in the tank has access to the pump cylinder 14. Preferably the base supports a screen 26 interposed between its inlet openings 24 and the opening 20 in the bottom of the cylinder. The cylinder 14 is made of brass or aluminum or other non-magnetic material.

2

The piston 16 is provided with inlet ports 28 in its end wall and said ports are controlled by a valve in the form of an extremely light disc 30 guided for movement toward and from the ports 28 by a centrally located pin or stem 32. To facilitate the flow of oil past the valve disc 30 when it is lifted to uncover the ports 28, said disc has an annular series of ports 34 disposed nearer its center than the ports 28 of the piston, and in addition, there is an annular clearance space 36 between the edge of the disc and the cylindrical wall of the piston 16. The piston 16 is reciprocated rapidly but with a relatively short stroke by electromagnetic means shown in Fig. 3 as comprising a field magnet 38 having a coil 40 and magnetic pole pieces 42 embracing the upper portion of the cylinder 14. By the application of an alternating or a pulsating current to the coil 40 through its lead wires 44, 46, the piston 16, which is composed of magnetic metal so as to constitute an armature for the field magnet, is subjected to rapid intermittent impulses causing it to be reciprocated or vibrated vertically as long as the current is applied to the coil 40.

25 This vibratory movement of the piston 16 operates to admit oil through the ports 28 and past the valve disc 30 so that the oil accumulates above said valve in the cylinder 14 and in the tube 48 which extends upwardly in the reservoir 10 from the cap 50 of the cylinder 14. At the upper end said tube 48 discharges into a trough 52 extending horizontally in the upper portion of the tank 10. At spaced intervals in its length said trough has a series of outlets 54, each leading from the lowest portion of the trough and each disposed above a feed tube 56, one of said tubes 56 being provided for each part or bearing which is to receive lubrication. Each tube 56 is supported at one end by resting in an opening in a flange or skirt 58 which depends from the forward edge of the trough 52; and the other end of the tube 56 is attached to a ring 60 carried loosely at the lower end of an adjusting screw 62. The tubes 56 are of capillary character so that when a drop of oil escapes from one of the openings 54 in the trough 52 and falls on to the inclined inner end portion 56a of the tube 56, the oil will flow downwardly along this inclined portion of the tube and across the adjacent open end of the tube whereupon a portion of the oil will be sucked into the tube by capillary action coupled with a syphon effect, while some of it may drip from the end of the tube back into the main supply in the reservoir 10. The syphon action 35 draws the oil upwardly along the inclined por-

30

50

55

tion 56a and thence through the downwardly inclined portion 56b of the tube for discharge through an outlet 56c which is located closely adjacent the ring 60. Said ring 60 rests upon a shouldered and tapered terminal 64 at the lower end of the adjusting screw 62 so that the oil emerging from the outlet 56c flows over the surface of this terminal and drips therefrom as indicated at 66. Each of the terminals 64 is disposed directly above the upwardly open end of a feed tube 68, and said tubes lead respectively to the various bearings or surfaces to be lubricated.

The rate of flow of the oil through the capillary tube 56 can be varied by altering the inclination of the longer portion 56b of the tube and this is done by adjusting the screw 62 upwardly or downwardly in its threaded mounting in the upper rail 70 of the sight feed frame 72. As seen in Figs. 1 and 2, said frame 72 carries a window 73 through which the feeding of the oil from each of the terminals 64 may be observed. A lock nut 74 secures each screw 62 at adjusted position. Such alteration of the inclination of the part 56b of the tube varies the siphon action by which the column of oil in the longer portion 56b draws the oil through the shorter portion 56a into the tube and through it and thus varies the rate at which the oil is fed from the tube 56 on to the terminal 64 and thence into the feed or delivery tube 68.

The provision of the trough 52 with relatively small outlet ports 54, through which the oil drips on to the several tubes 56, permits oil to accumulate in the trough to the level of the rear edge 52a thereof from which an inclined flange 52b serves as a spillway for the return of any excess oil to the reservoir 10. The accumulation of oil in the trough permits any foam formed therein to collect at the upper surface of the oil and thus eliminates the bubbles from the oil discharged at the ports 54 and drawn through the tubes 56.

As shown in Fig. 1, the frame 72 carries numerals designating the individual feed tubes 68 and to facilitate adjustment of the oil feed for any one of these tubes, the bearing to which each of them leads may be provided with a marker 76 carrying a similar designating numeral as shown in Fig. 4. The marker consists of a metallic angle plate having one leg perforated to admit the tube 68 so that a nut 78 serves to clamp the angle plate to the boss 80 through which oil is fed to the bearing 82. The other leg of the angle plate is thus presented in upstanding position for display of the numeral marked upon it.

To secure a neat appearance of the multiple oiler unit as installed upon the side wall of a machine or other supporting surface, the underside of the tank 10 is formed with a rib 84 having spaced notches 85 in which the tubes 68 are led from the front of the tank across its under surface. From the notches 85 the tubes converge toward the middle portion thereof where they are shown in Fig. 1 gathered behind a cleat or clamping plate 86. A longer cleat 88 is secured by screws 90 to the underside of the tank 10 in position to confine the horizontal portions of the tubes 68 in the notches 85 of the rib 84. The top wall of the tank 10 has a capped filler neck 11, through which the oil supply may be replenished at intervals.

The electro-magnetic pumping device herein shown is preferred because it dispenses with a more elaborate mechanism including a rotary electric motor, but the utility of the other features

of the invention is not confined to an apparatus employing this particular type of pump. When this pump is used, the valve disc 30 will be made preferably of Duralumin or some equally light material so as to respond promptly to the short rapid strokes of the piston operating in synchronism with the alterations or pulsations of the actuating current. The agitation of the oil by the pump will not necessarily produce foam at all times, but this may occur if the oil level in the reservoir 10 is rather low, and at such times the trough 52 affords an opportunity for the foam to separate from the main body of oil in the trough and to discharge over the crest of the trough at 52a.

The tubes 56 may be considered as resistance elements in the system since their resistance to flow and the consequent rate of flow to each of the bearings may be varied by adjusting the inclination of each individual tube 56, as already explained.

While there is shown and described herein certain structure embodying my invention and illustrative thereof, it is to be understood that the invention is not limited thereto or thereby, but embraces all modifications, variations and equivalents which may come within the scope of the appended claims.

I claim:

1. In a multiple oiler, in combination, a tank, an upwardly open trough supported above the oil level in said tank, said trough having a plurality of outlet ports spaced at intervals in its length at the bottom of the trough, pumping means adapted to elevate oil from a supply in said tank and to deliver said oil into the trough, resistance tubes registered respectively under said outlets and adapted to receive oil as it drips therefrom, and delivery tubes into which oil is discharged from the respective resistance tubes.

2. In a multiple oiler as defined in claim 1, each of said resistance tubes having a high point from which a longer portion and a shorter portion of the tube are both inclined downwardly toward its ends, the shorter portion of each tube being registered under one of the trough outlets and having an open end to receive the oil which drips from the trough outlet and flows over said open end.

3. In a multiple oiler as defined in claim 1, said resistance tubes having portions inclined downwardly toward the respective delivery tubes into which they discharge, and means to vary the inclination of each resistance tube independent of the others.

4. In a multiple oiler as defined in claim 1, said resistance tubes having portions inclined downwardly toward the respective delivery tubes into which they discharge, a vertically adjustable screw for each tube and a terminal by which each tube is engaged with one of said screws for adjustment of its inclination independently of the other tubes.

5. In a multiple oiler as defined in claim 1, said resistance tubes having portions inclined downwardly toward the respective delivery tubes into which they discharge, a vertically adjustable screw for each tube and a ring attached to the lower end of each resistance tube encircling said screw, said screw having a shoulder with which the ring is engaged, whereby adjustment of the screws varies the inclination of the tube to regulate the rate of flow through it.

6. In a multiple oiler as defined in claim 1, said resistance tubes having portions inclined down-

wardly toward the respective delivery tubes into which they discharge, a vertically adjustable screw for each tube and a terminal by which each tube is engaged with one of said screws for adjustment of its inclination independently of the other tubes, each screw having a downwardly tapering terminal disposed directly over the upwardly open end of a delivery tube, and each resistance tube having an opening adjacent the screw to permit oil to flow from the tube onto the surface of said tapered terminal and to drip therefrom into the delivery tube.

7. In a multiple oiler as defined in claim 1, said trough having a skirt depending from one edge of the trough and below the plane of the bottom of said trough, said skirt having openings at intervals to receive and support said resistance tubes in registration with the trough outlets.

8. In a multiple oiler, in combination, a tank, a receiver for oil mounted in the tank above the oil level therein, pumping means adapted to elevate oil from a supply in said tank into said receiver, said receiver having a plurality of outlet ports, a plurality of conduits supported in a plane inclined downwardly from a point below said ports and registered respectively adjacent their higher ends with said outlet ports so that oil discharging from said ports drops onto the said end of said conduits, delivery tubes positioned respectively adjacent the lower ends of said conduits to receive oil therefrom, and means for adjusting the inclination of said conduits individually to regulate the rate of flow of oil to each delivery tube.

9. In a multiple oiler, in combination, a tank, an upwardly open trough supported therein above the oil level, said trough having a plurality of outlet ports spaced apart in a lower portion of the trough, pumping means adapted to elevate oil from a supply in said tank and to deliver said oil into the trough, and means including a plurality of conduits below the bottom of said trough registered respectively with said outlet ports to receive oil which drips therefrom and to distribute said oil to separate parts to be lubricated.

10. In a multiple oiler as defined in claim 1, each of said resistance tubes having a high point from which a longer portion and a shorter portion of the tube are both inclined downwardly toward its ends, the shorter portion of each tube being registered under one of the trough outlets and having an open end to receive the oil which drips from the trough outlet and flows over said open end, said trough including a downwardly inclined flange extending from the upper edge of the trough above said open ends of the resistance tubes, said flange serving as a spillway for foam collecting on the surface of oil in the trough and extending far enough to carry said foam clear of the open ends of said tubes.

11. In a multiple oiler as defined in claim 1, said resistance tubes having portions inclined downwardly toward the respective delivery tubes into which they discharge, a vertically adjustable screw for each tube and a terminal by which each tube is engaged with one of said screws for adjustment of its inclination independently of the other tubes, each screw having a downwardly tapering terminal disposed directly over the upwardly open end of a delivery tube, and each resistance tube having an opening adjacent the screw to permit oil to flow from the tube onto the surface of said tapered terminal and

to drip therefrom into the delivery tube, said tank including a sight feed window disposed in a vertical plane opposite said tapered terminals, and a frame for said window, said screws being adjustable in threaded holes in a top member of said frame, and said upwardly open ends of the delivery tubes being supported by a bottom member of said frame respectively opposite said threaded holes.

10. In a multiple oiler, a tank, sight feed means associated therewith, said tank having a sight feed window including a frame therefor projecting from a vertical wall of the tank, a plurality of delivery tubes extending downwardly from the lower side of said frame at horizontally spaced positions, the bottom of said tank including a rib with downwardly open notches spaced to register with said tubes respectively and to receive said tubes when they are bent around the lower edge of the tank to extend across the under side of its bottom wall, together with a cleat removably secured over the notches of the rib to retain said tubes therein.

12. An oil dispensing and apportioning apparatus comprising a constant level reservoir having a plurality of discharge outlet ports adjacent the lowermost portion thereof for the gravitational discharge of oil from the reservoir at a relatively slow rate, means to maintain oil at a substantially constant level in said reservoir, means including a plurality of capillary conduits supported in a plane inclined to the horizontal below the discharge ports for intercepting and conveying to a part requiring lubricant at least a portion of the oil dripping from said discharge ports, and means for individually adjusting the inclination of said capillary conduits to control the rate of flow therethrough.

13. An oil dispensing and apportioning apparatus comprising a trough-shaped reservoir having a plurality of discharge outlet ports in the lowermost portion of its bottom for the gravitational discharge of oil at a relatively slow and uniform rate, means to maintain oil in said reservoir at a sufficiently high level to prevent foam from entering said ports, means for intercepting and conveying at least a portion of the oil discharged from said outlet ports to parts to be lubricated including a plurality of tubes of capillary dimensions having opposite end portions inclined with respect to each other, one of said end portions being provided with an inlet opening and the other of said end portions being provided with an outlet, and means for supporting a separate tube under each of said ports with the inlet end portion thereof disposed to intercept at least a portion of the oil discharging from said ports, and the outlet thereof disposed in a plane below the inlet opening to induce a flow of lubricant from said inlet opening to said outlet through the combined effect of capillary and siphon action.

14. An oil dispensing and apportioning apparatus comprising a main reservoir for oil, an auxiliary reservoir located above the normal level of the oil in the main reservoir and having a tapered bottom and a spillway for determining the level of the oil therein, a plurality of discharge ports in the lowermost portion of said inclined bottom for the gravitational discharge of oil from the auxiliary reservoir at a relatively slow uniform rate, means for pumping oil from said main reservoir to said auxiliary reservoir at a rate faster than the oil is discharged through said ports, and a separate capillary tube for each of

said discharge ports for intercepting and conveying to parts requiring lubricant at least a portion of the oil dripping from the ports, said tubes each being bent intermediate their ends to provide a relatively short inlet end portion fixedly supported and an outlet end portion supported for movement in a vertical plane to permit adjustment of the elevation of said latter end portion for producing a flow of oil through said tubes as a result of capillary and siphon action.

16. In a lubricator, the combination comprising a constant level reservoir, means forming a discharge outlet adjacent the lowermost portion of the reservoir for the gravitational discharge of lubricant from the reservoir, means to maintain lubricant at a substantially constant level in said reservoir, means for intercepting and conveying at least a portion of the lubricant discharged from said outlet to a part to be lubricated including a conduit of capillary dimensions bent along an intermediate portion thereof to form inclined end portions, and means for supporting said tube with an intermediate part of one of the end portions thereof registering with the discharge outlet in said reservoir for intercepting at least a portion of the lubricant discharged from said outlet, said tube being open at said end to form an inlet for receiving intercepted lubricant and having its opposite end disposed in a lower plane to produce a flow of lubricant through the tube as a result of capillary and siphon action.

17. In a lubricator, the combination comprising a constant level reservoir, means forming a discharge outlet adjacent the lowermost portion of the reservoir for the gravitational discharge of lubricant from the reservoir, means to maintain lubricant at a substantially constant level in said reservoir, means for intercepting at least a portion of the lubricant discharged from said outlet including a tube of capillary dimensions supported below and spaced from said outlet in a plane vertically aligned therewith, and means for conducting lubricant flowing from said capillary tube to the part to be lubricated.

18. In a lubricator, a reservoir, sight feed means for feeding oil from said reservoir to a plurality of parts requiring lubricant, including an auxiliary frame on said reservoir, a window in said frame, a plurality of delivery conduits having open inlet ends fixed to said auxiliary frame behind said window, resistance means for delivering oil at a relatively slow rate to said delivery conduits, said resistance means having outlets behind said window spaced above the inlet to said delivery conduits, and means including a spacer on the bottom wall of said reservoir for fixedly securing said tubes in spaced relation relative to each other at a point separated from the inlet ends thereof.

19. In a lubricator, a reservoir, sight feed means for feeding oil from said reservoir to a plurality of parts requiring lubricant, including an auxiliary frame on said reservoir, a window in said frame, a plurality of delivery conduits having open inlet ends fixed to said auxiliary frame behind said window, resistance means for delivering oil at a relatively slow rate to said delivery conduits, said resistance means having outlets behind said window spaced above the inlet to said delivery conduits, means including a spacer on the bottom wall of said reservoir for fixedly securing said tubes in spaced relation relative to each other at a point separated from the inlet ends thereof, and visible indicia associated with said delivery tubes corresponding respectively with similar indicia on the bearings to which said tubes lead.
